RELIGIOUS FLAG

Frank W. Clarke, Valley Stream, N. Y.

Application July 24, 1957, Serial No. 47,066

Term of patent 3½ years

(Cl. D29—17)

Fig. 2

The dominant features of the design reside in the representation of a cross above a representation of the earth disposed on the field of the flag.

The reverse side of the flag is of similar appearance.

I claim:

The ornamental design for a religious flag, substantially as shown and described.
